CLAIM

The ornamental design for an apple shaped ethylene absorbing device, as shown and described.

DESCRIPTION

FIG. 1 is a top perspective view of the apple shaped ethylene absorbing device.

FIG. 2 is a bottom perspective view of the apple shaped ethylene absorbing device.

FIG. 3 is a top plan view of the apple shaped ethylene absorbing device.

FIG. 4 is a bottom plan view of the apple shaped ethylene absorbing device.

FIG. 5 is a right side elevation view of the apple shaped ethylene absorbing device, the left side elevation view being a mirror image thereof.

FIG. 6 is a rear elevation of the apple shaped ethylene absorbing device.

FIG. 7 is a front elevation of the apple shaped ethylene absorbing device; and,

FIG. 8 is a sectional view taken along line 8—8 in FIG. 7.

The left side elevation is a mirror image of the view depicted in FIG. 4.

The broken lines of FIG. 8 depict internal structure, showing environment, and do not form a part of the claimed design.
